UNITED STATES PATENT OFFICE.

WILLIAM T. HANNA, OF CINCINNATI, OHIO, ASSIGNOR TO THE MECHANICAL CONSTRUCTION COMPANY, OF CINCINNATI, OHIO, A CORPORATION OF OHIO.

LOCOMOTIVE-TENDER STOKER MECHANISM.

1,239,101.

Specification of Letters Patent. Patented Sept. 4, 1917.

Application filed August 28, 1913. Serial No. 787,226.

To all whom it may concern:

Be it known that I, WILLIAM T. HANNA, a citizen of the United States, and resident of Cincinnati, in the county of Hamilton 5 and State of Ohio, have invented a new and useful Improvement in Locomotive-Tender Stoker Mechanism; and I do hereby declare the following to be a full, clear, and exact description thereof.

10 My invention relates to improvements in stokers which are particularly though not exclusively adapted for use on locomotive engines. This particular part of my invention is concerned with the means and mechanism 15 for conveying coal fuel from a hopper such as that of a tender of a locomotive to the fire box of the engine.

The invention has for its objects the taking of the fuel successively from all parts of 20 the hopper or tender in such manner that the conveying mechanism does not sustain the entire weight of the whole fuel mass but the opening from the hopper to the conveyer may be shifted at successive stages from one 25 part, usually the front of the tender hopper to the rear thereof, so that as the fuel at one part is exhausted, portions may be taken from progressively different parts of the mass. A further object is to provide means 30 to crush lumps of fuel to a size suitable for easy conveyance through the feed chute to the fuel distributing mechanism which mechanism is located within the fire door of the fire box. A further object is to provide means 35 for the relative movement between the tender and engine when under way on the road by providing a universal joint between the conveyer mechanism on the tender and the secondary mechanism on the engine. A further 40 object is to provide effective and compact driving means for the operation of the fuel conveying means as well as for the fuel feed and distributing mechanism which is to be used with this device.

45 With these and other objects as it will appear from the following description, the invention consists in the constructions and relative arrangement of parts and mode of operation the preferred embodiments of 50 which are illustrated in the accompanying drawing in which:

Figure 1 is a fragmentary view in plan of the hopper or tender and engine conveyer mechanisms forming the subject matter of this invention, parts being broken

away for clear illustration; Fig. 2 is a vertical section taken longitudinally of the hopper mechanism shown in Fig. 1; Fig. 3 is a detail plan view of the bridge which extends over the conveyer hopper on the 60 tender; Fig. 4 is a side elevation of the bridge member shown in Fig. 3; Figs. 5 and 6 comprise a plan and a side elevation respectively of the shiftable opening wings or segments for varying the position of the 65 opening from the tender hopper to the tender conveyer hopper; Fig. 7 is a view in elevation of one of the pivot pins by which the shiftable segments are pivoted to the conveyer hopper bridge; and Fig. 8 is an enlarged plan view of the tender conveyer 70 hopper with the bridge and segmental plates removed.

In the embodiment of my invention here selected for illustration 1 indicates in plan 75 view the forward end of the locomotive tender. 2 indicates diagrammatically the rear end of the frame of the engine of the locomotive. As is well known in practice the walls of the hopper in the tender slope convergingly to a floor area of comparatively small dimensions. Within and beneath this area I place my conveyer hopper 4, which may be, and preferably is, of inverted cone shape. Upon a flange 5 at the upper edge 80 of this conveyer hopper is mounted a bridge member 6 the forward end 7 (Fig. 3) of which, or that toward the cab, is of considerable width to afford a foot-way for the fireman. This wider portion is also of segmental shape as shown in Fig. 3, for the purpose hereinafter described. The opposite end of the bridge member is narrow and substantially straight. This bridge member is bolted to the flange 5 of the conveyer hopper through the bolt holes 9—9. This bridge member 6 is provided with a strengthening web 10 and a truss member 11 and at the center of the bridge is a circular hub 12 provided with upper and lower flanges 13 and 14 respectively, in which are pivot pin holes 15 for the reception of the segment pivot pins 15', said pins having enlarged heads 15² to prevent them from dropping entirely through the pivot holes. 95 100 105

In order to prevent the resting of the weight of the entire mass of the fuel in the tender hopper upon the conveyer mechanism within the conveyer hopper 4, it is necessary that there be only a reduced opening between 110

the tender hopper and said conveyer hopper. Furthermore, in order to facilitate the taking of fuel from all parts of the mass in the tender hopper it is necessary that it be possible to shift this opening from front to rear of the tender as the mass of fuel is reduced. It is also desirable that as the mass of fuel recedes to the rear of the tender hopper the flooring of the tender hopper over the conveyer hopper be restored or maintained intact so that the fireman may have ample foot-way for any desired operations in the tender. To this end a series of shiftable floor segments are used in conjunction with the bridge member 6 extending over the conveyer hopper. One of these segments is illustrated at 16, Figs. 5 and 6, and the series is shown in plan in Fig. 1, and in sectional view in Fig. 2. Each of these segments comprises a floor or cover plate 17 extending radially from the hub 18 and is braced by webs 19 and 20, Figs. 5 and 6. The hub 18 of the segment is perforated at center to receive the pivot pin 15'. These segment hubs are of a length to fit more or less accurately between the flanges 13 and 14 of the hub 12 of the bridge member 6 so that when placed in position the segmental pieces or floor segments may be pivoted on the bridge hub 12 and may be capable of swinging a limited distance toward or from the arms 7 or 8 of said bridge member. As seen in Fig. 2 these floor segments are mounted to swing beneath the edges of the widened end 7 or to the narrow end 8 of the bridge member and the outer ends of the segments rest upon the annular flange of the conveyer hopper 4. It is to be understood that the number of segments pivoted upon either side of the bridge member is just sufficient to close the entire opening between the tender hopper and the conveying hopper 4 when the edges of the segments upon either side of wider portion 7 of the bridge member 6 lie just beneath the opposite edges respectively of this wide portion and the widened portion of the bridge is made of a dimension equal to the area of two of these floor segments. When therefore it is desired to open communication between the tender hopper and the conveyer hopper one of these segments upon either or both sides of the widened portion 7 of the bridge member may be swung beneath such wide portion, thus leaving an opening in the floor of the tender hopper for access of coal to the conveyer hopper 4. It is to be understood, further, that this widened portion of the bridge member 6 is to be located at the forward end of the tender hopper so that the mass of the fuel at the forward end in the tender is first fed to the conveyer hopper. As the mass of fuel recedes to the rear, the next segment to the rear may be swung forward until it abuts against the first segment now lying

beneath the wide portion 7 of the bridge member 6. Thus the opening between the tender hopper and conveyer hopper is shifted by so much to the rear and this operation may be repeated until the entire mass of fuel in the tender is exhausted. It will be noted that as the segments are so shifted or swung to the front the flooring of the tender hopper is continually restored, giving ample foot-way to the fireman. It is also to be noted that segments upon either side of the bridge member may be alternately swung forward so that fuel is taken completely from side to side of the tender hopper. The small amount of fuel which may rest upon the bridge member itself may be readily dislodged and deposited through the opening left by the shifted segment. It is to be understood that my invention covers broadly the idea of producing a shiftable opening between the tender hopper and the conveying mechanism by which successive portions of the fuel mass may be fed to the conveyer while at the same time the conveyer is relieved of the weight of the entire fuel mass. 90

Having described the means and method for so feeding the fuel to the conveyer I will now describe the means for conveying the fuel from the conveyer hopper on the tender to the engine and thence to the fire box of the engine, and incidentally for cutting or crushing fuel lumps of excessive size to reduce the fuel to the most effective size for firing. 95

The conveyer hopper 4 is provided with a long journal bearing 22 which may be cast integral therewith and preferably over this bearing the body of the conveyer hopper has cast therewith a ridge 23, said bearing and ridge terminating at the rear in a gear casing 24 closed by a closer plate 25, Figs. 1 and 2. As will be seen in the plan view Fig. 1, the journal bearing 22 does not extend fore and aft axially of the tender but is arranged at an angle so that the conveyer tube hereinafter described may convey the fuel to a convenient point beneath the cab of the engine for the purpose hereinafter described. Cast integrally with the conveyer hopper is a conveyer trough 26 extending axially with the journal bearing 22 and within this trough is mounted a conveyer screw or worm 27 fixed upon a shaft 28 journaled in the long journal bearing 22, the conveyer screw being of the well known sectional form so that should any part become broken it may be readily replaced. At the rear of the screw shaft 28 is fixed a driving gear 29, Figs. 1 and 2, which meshes with a driving pinion 30 on the driving shaft 31 journaled in bearings cast in the conveyer hopper. This driving shaft 31 extends into a second gear box 32 beneath the conveyer hopper and is provided with a bevel gear 33 meshing with a second bevel 120

130

gear 34 mounted on the power shaft 35 of a suitable motor 36 located conveniently within one of the tool lockers 37 at the forward end of the tender. The motor 36 may 5 be conveniently operated by a steam connection (not shown) extending from the locomotive boiler.

The conveyer screw 27 carries the coal from the conveyer hopper 4 to a feed spout 10 38, Figs. 1 and 2, which spout is connected by a universal joint 39 with a delivery pipe or tube 40 which in turn over-lies at its outer end a small hopper 41 within which is mounted a second conveyer screw or worm 15 42. This second worm or screw may be driven in any desired manner, as, for example, by a universal jointed shaft 42^a connected with the shaft 31. The hopper 41 has a lateral opening 43 which communicates with a conveyer pipe 44 within which 20 is mounted a third conveyer screw 45 to raise the fuel to the curved delivery spout 46 which in turn delivers the fuel to fuel feed and distributing mechanism which is 25 located adjacent and within the fire door opening of the engine fire box. This fuel feed and delivery mechanism is not here illustrated, as in its specific form it does not form a part of the present invention 30 but it is to be understood broadly as a part of the combination and is illustrated and claimed in my co-pending application Serial No. 789,866, filed on the 15th day of September, 1913. The upright conveyer screw 35 45 is of peculiar construction to prevent jamming of the fuel as it is raised through the upward extending tube 44, that is to say, the shaft 47 of this conveyer worm 45 is of considerable diameter at the base and 40 tapers to a smaller diameter at the top, whereby a considerably greater space is afforded between the walls of the conveyer tube and the shaft at the top of said tube whereby any tendency of the fuel to pack 45 as it is raised is prevented by this greater space. In order to insure the forcing of the fuel from the hopper 41 through the lateral opening and into the upright conveyer tube 44 the conveyer worm 42 is provided at its 50 forward end with a reversed section 48 so that the junction of these two worm sections 42 and 48 serve to concentrate the fuel at the side opening 43. The upright worm 45 may be driven in any desired manner, as for 55 example by a short counter shaft 49 having a sprocket wheel 50 connected by a sprocket chain 51 with a sprocket wheel on the shaft 52 of worm 42, shafts 47 and 49 may be connected together by miter gears in the 60 ordinary manner.

In order to enable the stoker mechanism to handle fuel of various sizes, and particularly such for example as is known as "run of mine" coal, I provide adjacent the conveyer screw 27 a crushing knife 53 which

is of arc shape and arches across over the conveyer trough 26 just above and closely adjacent to the worm of the conveyer screw. It will be seen therefore that the fuel lumps as they are carried forward by the conveyer screw 27 will be reduced to a size sufficient to pass between the conveyer shaft and the inner surface of this crusher knife. In order to further reduce the size of the fuel pieces I may also provide a similar knife 54, 70 75 Fig. 8, extending around beneath the conveyer screw substantially opposite the knife 53, but the relative position of these knives may be altered as experience suggests. Thus it is immaterial what sizes of lumps of fuel are carried in the storage hopper provided they are capable of passing through the opening communicating with the conveyer hopper, for in all cases the fuel lumps will be reduced to a certain maximum size determined by the set of the knives with respect to the conveyer screw.

In order that there may be no possibility of choking of the fuel in the conveyer tube 40 the same may be tapered somewhat from 90 front to rear so that its forward diameter will be greater than the rear diameter.

It will be noted that the engine hopper 41 is arranged to one side and independently of the locomotive frame 2. This arrangement not only gives ready access to this hopper and the mechanism therein from the side of the engine but also positions the hopper at a convenient point beneath the deck of the cab where a trap door in the 100 cab floor may be located to give access directly to said hopper from the cab. This is especially advantageous if for any reason the tender conveyer mechanism is thrown out of commission and it is desirable to continue the stoker feed independently of the tender mechanism. This, furthermore, constitutes one of the main objects of arranging the conveyer screws and tubes from the tender conveyer to the engine stoker at an angle to the axial line of the tender and locomotive, and for the purpose of operation of the conveyer mechanism on the engine independently of the tender conveyer mechanism the power shaft 31 may have a clutch 110 of any suitable type interposed between itself and the pinion 30 so that the tender conveyer mechanism may be thrown out of operation while the engine conveyer mechanism continues to operate. The fireman in 115 this case opens the hatch or trap door communicating with the engine hopper 41 and feeds the fuel directly thereto by hand shoveling.

While I have herein described a particular embodiment of my invention it is to be understood that the same may be altered in details, arrangement of parts and mode of operation within the scope of the appended claims.

What I claim is:

1. In a furnace stoker mechanism, the combination in mechanism for feeding fuel to a fuel distributing mechanism, of a fuel supply mechanism comprising a storage hopper and a conveyer hopper, a conveyer trough and a feed screw therein for conveying fuel from said conveyer hopper to said distributing mechanism, said storage hopper having an opening communicating with said conveyer hopper and means to shift said opening relatively to said storage hopper as the fuel recedes from the initial position of said opening.
- 15 2. In a furnace stoker mechanism, the combination in mechanism for feeding fuel to a fuel distributing mechanism, of a fuel supply mechanism comprising a storage hopper and a conveyer hopper having means for conveying fuel from said conveyer hopper to said distributing mechanism, the floor of said storage hopper having an opening communicating with said conveyer hopper, a fixed bridging member extending over said opening and a plurality of closer members secured to said bridging member and adapted to be shifted successively to shift the point of communication between said hoppers from one part to another of said storage hopper as the fuel mass is exhausted in the latter.
- 30 3. In a furnace stoker mechanism, the combination in mechanism for feeding fuel to a fuel distributing mechanism, of a fuel supply mechanism comprising a storage hopper and a conveyer hopper having means for conveying fuel from said conveyer hopper to said distributing mechanism, the floor of said storage hopper having a circular opening therein, a bridging member extending over said opening, a plurality of closer members pivoted to said bridging member and extending to the periphery of said opening, said closer members being adapted to be swung successively to shift the point of communication between said hoppers as the fuel mass in said storage hoppers is exhausted.
- 35 4. In a furnace stoker mechanism, the combination in mechanism for feeding fuel to a fuel distributing mechanism, of a fuel supply mechanism comprising a storage hopper and a conveyer hopper having means for conveying fuel from said conveyer hopper to said distributing mechanism, the floor of said storage hopper having an opening, a bridging member extending over said opening, a plurality of closer members carried by said bridging member adapted normally to close said opening, one or more of said closer members being adapted to be moved beneath said bridging member to open communication between said hoppers, the remaining closer members being adapted to be shifted successively to shift the point of

communication between said hoppers from one part to another of said storage hopper as the fuel mass recedes from the successive points of communication.

5. In a furnace stoker mechanism, the combination in mechanism for feeding fuel to a fuel distributing mechanism, of a fuel supply mechanism comprising a storage hopper and a conveyer hopper having means for conveying fuel from said conveyer hopper to said distributing mechanism, the floor of said storage hopper having an opening communicating with said conveyer hopper, a bridging member spanning said opening and affording a foot-way thereover, a plurality of closer members supported by said bridging member and resting upon the edge of the said opening, said closer members being adapted to be shifted to open communication between said hoppers at the various points of said floor opening, said shifting of the closer members being adapted to shift the point of communication between said hoppers as the mass of fuel in the storage hopper recedes.

6. In a furnace stoker mechanism, the combination in mechanism for feeding fuel to a fuel distributing mechanism, of a fuel supply mechanism comprising a storage hopper and a conveyer hopper having means for conveying fuel from said conveyer hopper to said distributing mechanism, the floor of said storage hopper having a circular opening, a bridging member spanning said opening and affording a foot-way thereover, a circular series of closer members pivoted adjacent the center of said bridging member, one or both of said closer members adjacent one end of said bridging member being adapted to be shifted under said end to open communication between said hoppers, the other members of said series being adapted to be shifted successively toward said previously shifted closer members to shift the point or points of communication between said hoppers as the mass of fuel recedes from said points of communication successively.

7. In a furnace stoker mechanism, the combination in mechanism for feeding fuel to a fuel distributing mechanism, of a fuel supply mechanism comprising a storage hopper and a conveyer hopper having means for conveying fuel from said conveyer hopper to said distributing mechanism, the floor of said storage hopper having a circular opening communicating with said conveyer hopper, a bridging member spanning said opening diametrically, one end of said bridging member being wider than the other to form a foot-way over said opening, a circular series of segmental closer members pivoted at their inner ends adjacent the center of said bridging member and supported at their outer ends upon the edge

90

wall of said opening, the closer members adjacent said wider portion of the bridging member being adapted to be swung under said portion to open communication between said hoppers and the remaining closer members being adapted to be swung successively from their initial closing positions over against the previously shifted closer members to shift the point or points of communication between said hoppers as the fuel mass recedes from said points of communication.

8. In a furnace stoker mechanism, the combination in mechanism for feeding fuel to fuel distributing means, of fuel supply means comprising a storage hopper, a conveyer hopper located beneath the same and of substantially inverted cone shape, said storage hopper having an opening communicating with said conveyer hopper, means for varying the size and position of the communicating opening between said hoppers, a conveyer screw located in said con-

veyer hopper, said opening and changing means serving to relieve said conveyer screw from the total weight of the mass of fuel in said storage hopper.

9. In a fuel conveyer mechanism, the combination with a storage hopper and a conveyer hopper, the floor of said storage hopper having an opening communicating with said conveyer hopper, a fixed bridging member extending from said opening and a plurality of closer members secured to said bridging member and adapted to be shifted successively to shift the point of communication between said hoppers from one part to another of said storage hopper as the fuel mass is exhausted in the latter.

In testimony whereof, I the said WILLIAM T. HANNA have hereunto set my hand.

WILLIAM T. HANNA.
